UNITED STATES PATENT OFFICE.

FRANK L. SHELDON, OF RAILWAY, NEW JERSEY.

SHIRT.

SPECIFICATION forming part of Letters Patent No. 361,898, dated April 26, 1887.

Application filed February 7, 1887. Serial No. 236,764. (No model.)

To all whom it may concern:

Be it known that I, FRANK L. SHELDON, of Rahway, in the county of Union and State of New Jersey, have invented an Improvement 5 in Collars for Shirts, of which the following is a specification.

In the manufacture of shirts, especially woolen shirts, it is usual to attach to the body of the shirt a neckband, and to provide a turn-over collar as a separate piece connected at the upper edge of the neckband, and in this case the neckband frequently receives a lining or inlay of thicker material for stiffening the neckband. In this instance, however, the 10 seam between the neckband and the turn-over collar is objectionable, because it is liable to chafe and injure the neck of the wearer, and the lines of sewing or stitching are liable to be broken. In some cases the turn-over collar 15 has been attached directly to the upper end of the shirt-body or the yoke; but as there is in that case no neckband or stiffening the fold of the turn-over collar is liable to be irregular, and the turn-over collar does not set properly or uniformly.

The object of my invention is to obviate all these difficulties by introducing a stiffening between the outer and inner parts of the turn-over collar, so that while the turn-over collar 20 is connected directly to the body of the shirt the point at which the fold in the turn-over collar will occur is determined by the stiffening or inlay.

In the drawings, Figure 1 is a perspective view representing the upper part of the shirt and the turn-over collar. Fig. 2 shows the outer fabric of the turn-over collar, with the band or inlay attached thereto; and Fig. 3 is a section at the line *x x*, Fig. 1.

The shirt-body A is of any desired or convenient character, and the turn-over collar is composed of the two thicknesses B and C, which are cut out of the proper shape, and the fabric at the edges 2 3 4 is turned inwardly and united by one or more lines of stitching at 5.

The inlay or stiffening D is of suitable material, usually heavy muslin, cut on the bias,

and such inlay is narrowed or tapered toward the ends, as seen in Fig. 2, and it is united to the inner surface of one of the thicknesses B or C 50 of the turn-over collar, the inlay or stiffening being laid flat upon the fabric with its lower edges parallel to and at about one-quarter of an inch from the lower edge, 6, of the collar, and the lines of sewing by which the inlay or 55 stiffening is connected to the fabric of the collar should run all around the stiffening near the edges thereof.

The lower edges of the collar are to be turned inwardly, and the upper edges of the shirt-body at the neck portion inserted between the fabrics B and C of the collar and the parts united by sewing, there being one or two lines of stitching at 8. It is also usually preferable to unite the two fabrics of the turn-over collar 60 by a line or stitching at or near the upper edge of the inlay or stiffening D, so that the fold between the neck portion of the collar and the exterior of turned-over portion may be at or near this line of stitching. It will be now understood that the inlay or stiffening D 65 performs all the duty of a neckband, so far as causing the fold of the turn-over collar to assume a regular and defined position at the upper edge of the inlay, and that there are no 70 seams at or near the fold of the turn-over collar; hence the parts are more durable than in the shirts heretofore constructed.

I claim as my invention—

The combination, with the shirt-body and the two thicknesses of fabric forming the turn-over collar, of an inlay or stiffening, D, attached to the inner surface of one of said thicknesses and near the bottom edge thereof, so as to be between the two fabrics, the bottom edges 85 of the turn-over collar being connected directly to the shirt-body, substantially as set forth.

Signed by me this 1st day of February, 1887.

FRANK L. SHELDON.
